UNITED STATES PATENT OFFICE.

WILLIAM R. BEATTY, OF HAMMOND, INDIANA.

COMBINATION PUNCH, SHEAR, AND COPING MACHINE.

1,333,201.

Specification of Letters Patent.

Patented Mar. 9, 1920.

Application filed July 12, 1919. Serial No. 310,390.

To all whom it may concern:

Be it known that I, WILLIAM R. BEATTY, a citizen of the United States, residing at Hammond, in the county of Lake and State 5 of Indiana, have invented certain new and useful Improvements in Combination Punch, Shear, and Coping Machines, of which the following is a specification, reference being had therein to the accompanying drawings.

10 This invention relates to a combination punch, shear and coping machine, and has for its object the construction of a compact and efficient machine that will enable the operator to place the machine in a comparatively small space, and through which machine several operations or functions can be obtained that have heretofore only been accomplished through the medium of separate and independent machines.

20 Another object of the invention is the construction of a combination machine for working upon metal products, which embodies a peculiar and efficient frame that carries the different types of tool devices, as 25 well as the driving gear for these devices, together with a motor, all assembled in a compact and relatively simple manner for the purpose desired.

A still further object of my invention is 30 the construction of a combination machine for punching, shearing and coping, that is of a compact structure by reason of its peculiar frame, and which machine is so arranged as to have only one driving unit, and 35 geared up to this unit are tool devices that will enable the operator to quickly handle one class of work and then another class of work, without changing tools or without stopping the motor.

40 With these and other objects in view, my invention comprises certain novel constructions, combinations, and arrangements of parts as will be hereinafter specifically described, illustrated in the accompanying 45 drawings, and more particularly pointed out in the appended claims.

In the drawings,

Figure 1 is a view in side elevation of a machine constructed in accordance with the 50 present invention.

Fig. 2 is an end view in elevation, looking at the arch section and the motor carried thereon, while

55 Fig. 3 is an end view in elevation, looking at the punch devices.

Fig. 4 is a view in elevation of the frame,

with the tool devices and driving mechanism removed.

Fig. 5 is an enlarged view in elevation of the ram, while

Fig. 6 is a top plan view of the same.

Fig. 7 is an enlarged view in side elevation, of the yoke section.

Referring to the drawings by numerals, 1 comprises the foundation, upon which rests 65 the base 2 of the frame. The frame comprises the open-end section 3, the arch section 4, with the yoke section 5 spanning the driving gear gap 6, and connected at the lower end of its legs 7 and 8 to the open- 70 end section and the arch section, respectively. It will be understood that portions of the base 2 are preferably integral with the open-end section 3 and the arch section 4, and comprise a necessary part of these 75 sections. The base is preferably divided at 9, and this divided structure is connected by fastening means, as bolts or rivets 10 (Fig. 1).

The open-end section 3 is provided with 80 punching tools 11; this open-end section constitutes, with its coördinate parts, a punching machine combined in a peculiar manner in the combination that I have invented. The punching tools are driven by 85 the main or primary shaft 12, which shaft is formed in sections, and upon the contiguous inner ends (Fig. 1) are suitably secured clutch members 13. The clutch members 13 are actuated by levers 14, pivotally mounted 90 at 15 upon apertured ears 16 (Fig. 4) that are integral with the sections 3 and 4. These ears extend into driving gear gap 6, and, consequently, the levers 14 are pivotally mounted within gap 6.

The yoke section 5 comprises a body 5^a provided with the long depending leg 7 and the short leg 8. The lower end of leg 7 rests upon the top of the integral bracket 17, on section 3, and the lower end of the short leg 8 rests upon integral bracket 18 of the section 4. The lower ends or feet of legs 7 and 8 are securely fastened to brackets 17 and 18 by means of preferably bolts 19. An auxiliary shaft 20 is journaled upon the upper 105 portions of the legs 7 and 8, and attached to one end of shaft 20 is fly-wheel 21, and at the opposite end is gear wheel 22, which wheel meshes with the small gear 23 of the motor 24; the motor 24 is fastened to the 110 top of the arch section 4 by means of preferably a side bracket 25 which is bolted at

26 to the top of the arch section 4 (Fig. 2). Within the yoke, and fixedly secured to the auxiliary shaft 20, is a small gear 27, meshing with the large driving gear 28. The 5 large or primary gear 28 is fixedly secured to portions of the primary shaft 12, and gear 28 is fastened to the clutch members 13. A bracket 29 is bolted to the lower end of the long leg 7 of the yoke section, and 10 another bracket 29^a is bolted to the integral bracket 18, within the gap 6. Pivottally mounted upon brackets 29 and 29^a are the pedal-actuated devices 30 for shifting or actuating the clutch devices for causing either 15 end of the primary shaft 12 to be driven with respect to the primary gear 28, at the will of the operator, for operating the tool devices carried by either section 3 or 4.

It will be noted that within the driving 20 gear gap is mounted driving means controlled by a clutch mechanism for driving, at the will of the operator, either or both the metal-working tools carried by the open-end section or the arch section. The specific 25 structure of these tool devices is subject matter for separate applications for Letters Patent and are not specifically described in this application as I make no claim for the specific type or structure of these tool devices.

30 The arch section is provided with plates or guide means 31, between which is slidably mounted ram 32. This ram comprises a central body 33, reinforced on each side by vertically-extending webs 34, and its base 35 is provided with a plurality of apertures 36, in which apertures 36 are placed the bolts 37, whereby parts of the tool devices are directly bolted to the ram 32. The ram is provided with end flanges 38 which slidably engage the guiding plates 31, and the ram is in-cut at 39, forming pockets (39), in which pockets are seated the lower ends of eccentrics 40 (Fig. 1); these eccentrics are carried by shaft 12, and when shaft 12 45 is rotated, the eccentrics will raise and lower the ram 32. Apertures 41 (Figs. 5 and 6) are formed in the flanged ends 38 of the ram, and registering with these apertures 41, in the same horizontal plane, are pockets 42, which apertures 41 and pockets 42 receive pins or suitable fastening means whereby the eccentrics 40 are pivotally fastened to the ram 32.

The arch section is provided with a bolster 55 43, to which bolster is fastened, by means of bolts 44, parts of the tool devices; it will, therefore, be seen that bolts 37, carried by the ram, and bolts 44, carried by the bolster, provide fastening means for attaching the tool devices to the arch section of the frame of the machine. In Fig. 1, I have shown the tool devices carried by the arch

section being a flat bar shears 45, a round bar shears 46, and an angle bar shears 47. Secured to the outer face of the arch section 65 is a coping tool device 48. All of these devices are actuated or driven through the medium of the main or primary shaft 12. It will be seen that I have produced a compact machine, in which one primary sec- 70 tional driving shaft is coupled by a clutch mechanism with driving means, whereby a plurality of different types of tool devices may be driven or actuated from the same source of power, without necessitating the 75 changing of the tools or the stopping of the machine, since the machine is entirely under the control of the operator.

From the foregoing description, it is to be understood that I have invented a frame, 80 and associated with the frame is a plurality of metal-working devices, all driven from the same driving unit, and all arranged, by reason of the peculiar structure of my machine, in a very compact and efficient manner. I 85 do not limit myself to the frame, *per se*, as the only novelty in this case, as certain other combinations are specified, and, therefore, I desire it to be clearly understood that in the extensive manufacture of this machine, it 90 may be found necessary and desirable to make certain minor changes or alterations as shall appear to one skilled in the art to which this invention relates; therefore, I 95 reserve the right to make such alterations or changes or deviations as shall fairly fall within the scope of the appended claims.

What I claim is:

1. In a machine of the class described, the combination of a frame, a driving shaft 100 journaled upon said frame, a ram including a body and flanged ends, said body and flanged ends provided with eccentric receiving pockets and each end provided with a horizontal aperture, the body contiguous to 105 the pocket provided with a second pocket contiguous to the eccentric receiving pocket, eccentrics on said shaft and seated in said eccentric receiving pockets of the ram, fastening means extending through the apertures of the flanged ends of the ram and through the eccentrics and into the second pockets in alignment with the apertures on the ends of the ram, and a metal-working device carried by the ram and the frame. 110 115

2. A frame for a machine of the class described comprising an open-end section and an arch section provided with a driving gear gap therebetween, and coping means supporting means formed upon the outer side 120 or end of the arch section.

In testimony whereof I hereunto affix my signature.

WILLIAM R. BEATTY.
